UNITED STATES PATENT OFFICE.

ADOLPH G. KAUFMAN, OF NEW YORK, N. Y., ASSIGNOR OF ONE-HALF TO
BENJAMIN L. WEIL AND BERTHOLD L. WEIL, OF NEW YORK, N. Y.

BOTTLE-CAP.

No. 851,424.

Specification of Letters Patent.

Patented April 23, 1907.

Application filed May 25, 1906. Serial No 318,607.

To all whom it may concern:

Be it known that I, ADOLPH G. KAUFMAN, a citizen of the United States, and a resident of the borough of Manhattan, city, county, and State of New York, have invented certain new and useful Improvements in Bottle-Caps, of which the following is a specification.

My invention relates to closures for bottles, jars or other receptacles, and particularly to so-called bottle caps, that is closures which are fitted over the mouth of the bottle and part of the neck.

The object of my invention is to so construct the bottle cap that it may be removed readily without the use of a tool, although such tool may be used if desired.

The accompanying drawings illustrate several ways of carrying out my invention.

Figure 1 is a vertical section showing the neck of a bottle with my improved cap applied thereto; Fig. 2 is a top view of such cap; Fig. 3 is a side elevation of the bottle neck and cap; Fig. 4 is a vertical section showing another form of my invention; Fig. 5 is a top view of the cap shown in Fig. 4, and Fig. 6 is a vertical section of another form of washer and sealing disk.

The bottle neck A is provided with the usual bead A' forming a shoulder to hold the edge of the cap. As illustrated in Fig. 1; 2 and 3, the cap has a convex edge portion B adapted to fit over the bead A', and preferably the lower edge of said portion B is made wavy or with alternating teeth B' and indentations B'', the tooth portions being strengthened by vertical ribs B³ while the intervening notch portions are left relatively weak. A dome-shaped releasing portion B⁴ is located at the center of the cap and preferably provided with radiating ribs B⁵ to strengthen it. This releasing portion, which rises above the edge portion or marginal portion B, is connected therewith by a re-entering flange portion B⁶. Through the throat or contraction B⁷ thus formed is projected the contracted neck C' of a sealing disk C made of material which will not be corroded by the contents of the bottle, and having a bottom flange C² adapted to engage the end surface of the bottle neck. Between the flange C² and the marginal portion B is

clamped the inner edge of a packing ring D made of suitable material such as rubber. This packing ring or washer which engages the upper or end surface of the bottle neck, is thus securely connected with the other parts of the cap. The tooth portions B' may be provided with outward projections B⁸ at their lower ends.

A bottle closed with my improved cap is not liable to leak, but may be opened readily in the following manner: A downward pressure or blow is exerted on the dome-shaped releasing portion B⁴, and by what may be termed a lever action (the contraction or neck B⁷ forming a fulcrum) the lower edge of the cap is caused to swing outward, thus releasing the cap from the bottle. The same result may be obtained, of course, by pressing or knocking the bottle upward against the lower surface of a table or other article. If desired, however, the customary opening tool may be used, the prongs or projections B⁸ affording the necessary purchase.

The form of construction shown in Figs. 4 and 5 differs from that first described by the use of a somewhat different releasing portion. This releasing portion B⁹ is also raised or dome-shaped, but instead of having radial ribs, it is provided with annular ribs B¹⁰. Furthermore, the reentering portion or throat B⁶, B⁷ of Figs. 1 and 3 is omitted. Instead of the packing ring D and sealing disk C, I employ a single piece D' made of cork or other suitable material which at its edge is clamped between the mouth of the bottle and the inner edge of the marginal portion B. This piece D' forms at the same time a sealing disk and a packing ring. In Fig. 6, I have illustrated another form of a sealing disk and packing ring. The sealing disk C³ has a flange made with an annular groove C⁴ into which projects the inner edge of the packing ring D² made of rubber or other suitable material. This combined packing ring and sealing disk may be employed on either of the forms of my invention hereinbefore described.

It will be seen by reference to Figs. 1 and 4, that the line of connection of the releasing portion B⁴ or B⁹ with the marginal portion B, is within the lines indicating the cylindrical inner surface of the bottle neck; owing to this arrangement, the releasing portion exerts the

lever action hereinbefore described to free the marginal portion B from the bottle or other receptacle.

I claim as my invention:

- 5 1. A bottle or other receptacle having an external enlargement at the mouth, in combination with a cap having a marginal portion adapted to fit said enlargement, and a raised central releasing portion movable toward the receptacle to unlock the cap therefrom, the line of connection of the releasing portion with the marginal portion being within the continuation of the mouth's inner surface.
- 10 2. As a means for sealing bottles and other receptacles, a cap provided with a marginal portion adapted to engage an enlargement of the receptacle and having alternate teeth and notches, and also provided with a central releasing portion movable toward the mouth of the receptacle to unlock the cap therefrom.
- 15 3. As a means for sealing bottles and other receptacles, a cap provided with a marginal portion having teeth strengthened by ribs and relatively weak portions between said

teeth, and also provided with a central releasing portion movable toward the mouth of the receptacle to unlock the cap therefrom.

4. As a means for closing bottles and other receptacles, a cap provided with a marginal portion having teeth alternating with notches, and also provided with a raised releasing portion movable toward the mouth of the receptacle to unlock the cap therefrom.

5. As a means for closing bottles and other receptacles, a cap provided with a marginal portion adapted to fit an enlargement at the mouth of the bottle and having strengthening ribs and outward projections at the lower ends of said ribs, and also provided with a raised releasing portion movable toward the mouth of the receptacle to unlock the cap therefrom.

In testimony whereof, I have hereunto signed my name in the presence of two subscribing witnesses.

ADOLPH G. KAUFMAN.
